UNITED STATES PATENT OFFICE.

JAMES ENSLEY HIXSON, OF LOS ANGELES, CALIFORNIA, ASSIGNOR TO MARTIN A. LEACHE, OF LOS ANGELES, CALIFORNIA.

VEHICLE.

1,427,387.

Specification of Letters Patent. Patented Aug. 29, 1922.

Application filed March 3, 1919. Serial No. 280,506.

To all whom it may concern:

Be it known that I, JAMES E. HIXSON, a citizen of the United States, residing at Los Angeles, in the county of Los Angeles 5 and State of California, have invented a new and useful Vehicle, of which the following is a specification.

This invention relates to vehicles and especially to that type of vehicles having 10 curtains to close the sides thereof, and an object of the invention is to provide a construction adapted to permit of ready opening and closing of the curtains and retaining of the curtains at any desired degree of 15 opening.

Another object is to provide a construction which is of neat appearance.

Another object is to provide a construction which will permit the curtains to be 20 readily detached from the top, when it is desirable to repair the curtains.

Another object is to provide a construction which, when the curtains are in open 25 position, will permit the detachment of the front and intermediate curtain guide standards when it is not desired to close the curtains.

Another object is to provide a curtain construction which will prevent flapping of the 30 curtains to a large extent when the curtains are drawn slightly for shading purposes and the front and intermediate curtain guide standards are detached.

Other objects and advantages will appear 35 in the subjoined detailed description.

The accompanying drawings illustrate the invention:

Figure 1 is a side elevation of a vehicle's upper portion constructed in accordance 40 with the provisions of this invention.

Fig. 2 is a fragmental elevation mainly in vertical mid section on line indicated by x^2-x^2 , Fig. 3, the curtains on the near side being in raised position.

Fig. 3 is a plan section on line indicated by x^3-x^3 , Fig. 2, the top-lining and seats being omitted.

Fig. 4 is an enlarged fragmental sectional elevation on line indicated by x^4-x^4 , Fig. 50 1, one of the curtains being in raised position.

Fig. 5 is an enlarged fragmental elevation, mainly in section on line indicated by x^5-x^5 , Fig. 1.

Fig. 6 is an elevation from the left of Fig.

5, portions of the standard being shown in section.

Fig. 7 is a side elevation of one of the curtain frames.

Fig. 8 is an enlarged fragmental plan section on line indicated by x^6-x^6 , Fig. 7.

Fig. 9 is a side view of one of the top-lining supporting members.

The vehicle is provided with a body 1 of any suitable form and construction and attached at its rear to the body 1 is a top 2 which may be provided with a lining 3 to form an enclosed curtain-receiving space 4. It is not necessary to utilize the lining 3, which is only being used to improve the appearance of the vehicle; therefore the lining may be omitted if the constructor so desires. The frame of the top 2 is indicated at 5 and fastened at their outer ends to the frame 5 are inwardly projecting 70 transversely extending curtain guides in the form of channeled or grooved members 6, said members being provided near their outer ends with ears 7 fastened by screws or bolts 8 to the frame 5, as clearly shown 75 in Fig. 4. The members 6 are arranged in pairs and the members of each pair extend from opposite sides of the frames and overlap one another and are fastened together by welding or any suitable means. 80

Aligned with the outer ends of the guide members 6 are upright curtain guides in the form of grooved or channeled members 9 forming standards which, when in place, may aid in supporting the top 2, each standard being provided at its upper end with an ear 10 adapted to be fastened to the frame 5, and each standard being provided at its lower end with an ear 11 adapted to be fastened to the upper margin of the body 1. The ears 10, 11 of the rear pair of standards 9 may be permanently fastened by rivets 12 or their equivalents to the frame 5 and body 1. Each pair of guides 6 together with the associated pair of oppositely disposed guides 9 form a sectional bow, to which the top is fastened, the members 6 constituting one section and the members 9 constituting two other sections. Preferably the ears 10, 11 of the intermediate and forward standards 9 are detachably connected with the top and body respectively, and the means for detachably connecting said ears may be of any suitable construction. In the drawings, see es- 105 110

especially Figs. 5 and 6, the ears 10 and 11 of the intermediate and forward standards 9 are provided with perforations 13 through which project thumb screws 14 that are 5 screw-threaded into the frame 5 or body 1, as the case may be. Each guide 6 together with its associated standard 9 thus forms a grooved or channeled way extending from the upper margin of the body 1 to the side 10 margin of the top 2, thence transversely into said top. The guides are curved at their outer ends as indicated at 6' so as to exactly register with the upper ends of the standards 9.

15 Extending between each two adjacent ways 6, 9 at both sides of the vehicle are curtains, each curtain comprising a flexible frame 15 and a covering of any suitable material fastened to said frame. In the instance shown in the drawings each of the 20 coverings comprises an opaque member 16 and a transparent panel 17. The member 16 may be made of any suitable flexible curtain material and the transparent panels 25 17 may be made of isinglass, celluloid or the like. Each frame 15 is rectangular and comprises substantially rigid end rods 18 and flexible side strips 19 made of spring steel so as to be resilient. The resilient strips 30 19 are fastened at their ends by rivets 20 or their equivalents to the ends of the end rods 18.

The curtain side strips 19 are accommodated in the grooves 21 of the guides 6, 9 35 so that the curtains can be drawn from closed position in the top 2 downward toward the body 1 to shut in the space between the top and body. Thus it is clear that the curtains are shiftably mounted in the top and are 40 adapted to be drawn downward to any desired degree, the flexibility of the strips 19 readily permitting the curtain frames to slide in the curved portions 6' from the guides 6 to the guides 9 and from the guides 45 9 to the guides 6; and the expansive force of the strips 19 producing sufficient friction between the curtain and the side walls of the grooves 21 of the guides to hold the curtains in whatever positions they may be 50 adjusted.

The margins of the lining 3 adjacent the curtains are spaced from the top frame 5 and are suitably connected with said frame by supporting members 22 that may be in 55 the form of rods to which the lining is sewed. The rods 22 are bent at one end to form fastening flanges 29 which are attached by screws 23 or their equivalents to the frame 5. The rods 22 are provided with eyes 24 60 which engage screw-threaded studs 25 projecting inwardly from the curved portions 6' of the guides 6, there being nuts 26 on the studs to prevent the rods from slipping off of said studs. Each stud may be provided with a washer 27 between the eye 24

and nut 26. Thus it is clear that the curtains can be readily moved to and from the top 2 through the slots or spaces 28 existing between the rods 22 and frame 5.

The invention operates as follows: Assuming that the parts are in the positions shown in Fig. 1, the curtains being closed, to open the curtains to any degree whatsoever it is only necessary to push upward against the lower edge of the curtain and the curtains will then slide into the top 2. When the curtains are in full open position, they overlap one another in the top 2 to some extent, the overlapping arrangement being necessary in some instances to 80 prevent interference of the curtains with one another when they are being operated. When it is desired to dispense with the closed car effect, the curtains will be raised to full open position and the forward and intermediate standards 9 will be detached from the body and top by removing the thumb screws 14 so as to release said standards, whereupon said standards may be stored away under the seat of the vehicle or 90 in any other convenient place.

An advantage of the spring strips is that sufficient stiffness is given thereby to the curtains to hold the projecting portion of the curtains against flapping in the wind 95 when the curtains are in partly drawn positions. This is especially useful since it enables the curtains to be employed to shade the interior of the vehicle, to some extent, without it being necessary to place the forward and intermediate standards 9 in their 100 curtain guiding positions.

The invention is not limited in its broader phases to the exact details of construction shown in the drawings and above described, 105 but embraces such changes and modifications as lie within the spirit and scope of the appended claims.

I claim:

1. In a vehicle, the combination of a body, 110 a top frame for the body, guides in the top fastened at their outer ends to the side members of the frame and extending crosswise thereof, the outer end portions of the guides being curved downwardly adjacent the 115 frame side members, other guides alined with the curved ends of the first named guides and secured at their upper ends to the frame side members and at their lower ends to the body, rods extending beneath 120 the first guides parallel with the side members of the frame and secured to said members and spaced therefrom, a lining fastened at its side margins to the rods and at its 125 end margins to the end members of the frame, and curtains shiftable between the guides and through the spaces between the frame side members and rods.

2. In a vehicle, a body, a top frame for the body, guides in the top fastened at their 130

outer ends to the frame and extending transversely thereof, other guides aligned with the first named guides and extending from the top to the body, rods at opposite sides 5 of the frame fastened at their ends to the frame and provided with eyes, studs projecting from the outer ends of some of the first named guides and projecting through the eyes, means on the studs to hold the rods 10 on the studs, and curtains shiftable between the guides between the rods and the frame.

3. In a vehicle, a body, a top frame for the body, guides extending transversely of the top from both sides thereof and spaced at 15 their inner ends from said top and downwardly curved at their outer ends, the guides

of one side having their inner ends fastened to the inner ends of the guides of the other side, means connecting the curved outer ends of the guides to the upper face of the frame, 20 other guides aligned with the outer ends of the first named guides and extending from the top to the body, means fastening the ends of the last named guides to the outer faces of the top and body respectively, and 25 curtains shiftably engaging the guides.

Signed at Los Angeles, California, this 21st day of February, 1919.

JAMES ENSLEY HIXSON.
